UNITED STATES PATENT OFFICE.

FRANCIS JERDONE, JR., OF TOLEDO, OHIO, ASSIGNOR TO THE WILLYS-OVERLAND COMPANY, OF TOLEDO, OHIO, A CORPORATION OF OHIO.

HUB-CAP-LOCKING DEVICE.

Application filed February 24, 1919. Serial No. 278,773.

To all whom it may concern:

Be it known that I, FRANCIS JERDONE, Jr., residing at Toledo, county of Lucas, State of Ohio, have invented certain new and useful Improvements in Hub-Cap-Locking Devices, of which I declare the following to be a full, clear, and exact description.

My invention relates to hub cap locking devices, and has for its object to simplify the construction of devices of this kind, and to reduce the number of parts required to accomplish the desired results, thereby effecting a reduction in the cost of manufacture of a device of this character.

15 A further object of the invention is to provide a hub cap locking device which is simple in operation, and which is actuated automatically to release position by the tool used for removing the cap from the hub.

20 A further object of the invention is to provide a one piece locking device for retaining the hub cap in proper position upon the hub, said device being adapted to extend into locking engagement with the hub when in normal position, and to be moved to release position by a wrench or other tool adapted for use in removing the hub cap from the hub.

25 Still another object of the invention is to provide a circular spring member, one end of which is fixed upon the hub cap and the other end provided with a lateral or up-standing projection adapted to normally extend into locking engagement with the hub or a suitable holding member fixed thereon.

30 To these and other ends the invention comprises certain novel features of construction and arrangement of parts as will herein-after be more fully pointed out in the appended claims, it being understood that the locking device is susceptible to various modifications in the detailed construction thereof without departing from the spirit of the invention as expressed in the claims.

35 A structure constituting one embodiment of my invention is illustrated in the accompanying drawings, forming a part of this specification, in which:

40 Figure I is a fragmentary, sectional elevation of a wheel hub and cap secured thereon.

45 Figure II is a front elevation of the hub, partly in section, showing the hub cap locking device in normal locking position.

50 Figure III is a detail, side elevation on an

enlarged scale of the locking member shown in Figure II.

Figure IV is an enlarged detailed perspective view of the upper end of the locking device.

55 Figure V is a similar view of a slightly modified form of the invention.

Figures VI and VII are detailed perspective views of another modification of the invention which represent different 60 steps in the process of manufacture of the device.

65 Figure VIII is a detailed perspective view of a slightly modified form of the invention over that shown in Figure VII.

70 Figure IX is a fragmentary sectional elevation of a hub similar to that shown in Figure I, embodying a slightly modified form of locking device.

75 Figure X is a front elevation and part sectional view of the hub shown in Figure IX with the spring in normal locking position.

80 Figure XI is a fragmentary sectional elevation of a hub showing still another modified form of the invention.

85 Figure XII is a detail perspective view of the locking member shown in Figure XI, and

90 Figure XIII is a similar view of a locking member having the locking projection formed integral with the spring.

95 Similar reference numerals refer to similar parts throughout the several views of the drawings.

100 Heretofore in the construction of hub cap locking devices it has been customary to provide a yieldable or spring-like member in connection with a pivoted latch for preventing the accidental displacement of the hub cap. Many forms of locking devices embodying this general idea have been worked out, but so far as I am aware there have been none provided in which the locking portion of the device is formed integral with or made rigid upon the yieldable member for holding said device in locking engagement with the hub or some form of projection thereon.

105 Referring to the drawings, 10 represents the outer and 11 the inner hub portions of the wheel, said portions being provided with co-operating annular inclined surfaces 12 and 13 respectively which are adapted to lock said parts to prevent rotation of the 110

one upon the other. The inner hub member 11 is adapted to receive the tapered ends 15 of the axle 16 which is suitably keyed upon said hub member, said axle being held against longitudinal displacement by a nut 17, as shown in Figure I. The inner hub member 11 adjacent its outer end is provided with an annular flange 18 which is threaded externally to receive the inner hub cap member 19 which is riveted or otherwise secured to the outer cap member 20, the latter being provided with a tapered or cone shaped face 21 adapted to seat upon a correspondingly shaped and outwardly inclined portion 22 of the outer hub member 12, said portion 22 being provided with an inwardly inclined portion 23 having a circular opening substantially of a diameter equal to the outside diameter of the cap member 20. The portions 22 and 23 of the outer hub member extend substantially at a right angle to each other and between their inner faces a recess 24 is formed around the hub cap member 20. Within this recess and upon the inner face of said portion 23 is positioned a ring 25 having the laterally extending fingers 25' spaced at suitable intervals, said ring and fingers being preferably secured in position by spot welding. It will be understood that these parts are merely illustrative of one form of a latch holding device and that any other suitable form may be substituted therefor to engage the yieldable locking member which will presently be described.

It will be noted from Figure I that the inner cap member 19 is considerably reduced at its outer end where it connects with the outer cap member 20, thereby providing an annular recess 26, in which is mounted the yieldable locking member indicated generally at 27. The locking member 27 comprises a semi-circular or curved spring, preferably formed of spring wire, one end of which is provided with a right angle portion 28 seated in an aperture formed in the wall of the outer cap member 20 as shown in Figure II. The opposite end of the semi-circular spring member 27 is bent to form an outwardly extending loop 29, which is inclined downwardly as shown in Figure III, and provided with an upstanding locking projection 30 adapted to extend through an aperture in the wall of the outer cap member 20, and into engagement with one of the fingers 25' within the recess 24 formed by the annular portions 22 and 23 of the outer hub member 12. In the construction of the locking end 60 of the spring member 27 the loop 29 and the upstanding locking projection 30 thereon may be formed at one operation in a suitable die constructed for the purpose, the loop being inclined downwardly if preferred at the same time and by the same machine

in which said loop is constructed. It will be noted that the locking member 27 is formed of spring wire, which is peculiarly adapted for the purpose intended. The particular advantage in forming the loop 29 of round material lies in the fact that when the side portions 31 of the loop are bent into parallel relation, as shown in Figure IV, and then inclined downwardly, said side portions form a guideway 32 for receiving one of the pins or projections on the spanner or cap removing tool (not shown) which are adapted to project through the apertures 33 in the outer face of the cap member 20. During this operation one of said pins or projections will be forced along the inclined guideway to effect a depression of the upstanding locking portion 30 of the spring 27, said upstanding portion being depressed sufficiently to clear the locking finger 25' without disengaging the cap portion 20, after which the turning of the cap by means of the spanner is effected to permit its removal from the hub. The spring member 27, therefore, can not be accidentally displaced by the use of the spanner or other tool in removing the cap from the hub. The upstanding portion 30 of the locking member is preferably bent up from the outer side portion of the loop 29, although it may be attached to the loop or to the curved portion of the spring adjacent the loop if desired. The lower or outer end of the loop 29 as shown in Figure I projects in line with one of the apertures 33 in the outer face of the cap portion 20 in such a way that when the pin on the spanner is projected through the aperture it will immediately engage said loop between the side portions 31, as previously stated.

In the modification shown in Figure V, the loop is depressed at the point where it is bent upon itself, as indicated at 34, whereby the spanner pin may be more readily guided into proper position upon the loop.

While I have shown that portion of the locking device which is engaged by the spanner pin as being in the form of a loop, it will be understood that said portion may be formed of one solid grooved piece if desired.

In the construction of the modified form of the invention shown in Figures VI and VII the spring wire is first formed as shown in Figure IV, and is then flattened out as indicated at 35 in Figure VI. The flattened portion is then curved as indicated at 36 in Figure VII, preferably by the use of a suitable die or other tool or machine suitable for the purpose. It will be understood, of course, that the flattening and curving of said member may be effected at one operation by the use of a machine pro-

vided for the purpose if so desired. It will be noted from Figures VI and VII that although the loop is flattened and curved, the side portions thereof still remain in spaced relation except at the point where the bend is made, the same as in Figure IV. However, in the modified form shown in Figure VIII said side portions are united or welded together for substantially their full length, as indicated at 37. The curved portions 36 and 37 both extend downwardly and outwardly and are thereby inclined relatively to the horizontal axis of the hub, and each of said members forms an inclined guideway on which the pin of the spanner is adapted to ride when forced inwardly by the application of the wrench to the hub cap for the purpose of unscrewing the same; it being understood that in any of the modifications shown and in the preferred form of the invention, whenever the wrench is in position to effect a turning or unscrewing of the hub cap, that the upstanding locking portion 30 of the device will be depressed sufficiently to disengage the locking fingers 25' or any other form of locking projection extending in the path of said portion 30.

While I have shown the spring 27 and the locking portion 30 as being integral, it will be understood that the latter may be detachable, though rigidly connected with the former, if desired, as it is not absolutely essential that these parts be made in one piece as shown. It is thought, however, at the present time, that this device will be more satisfactory and can be manufactured cheaper if made in one piece, as the preferred form shows.

40 In the modification shown in Figures IX and X the spring 38 is provided with a circular loop 39 which is preferably inclined outwardly as shown in Figure IX in position to receive the pin on the spanner when the latter is applied to the hub to remove the cap therefrom, it being understood that with the pin projecting through the loop, the turning of the spanner will depress said loop and cause the upstanding projection thereon to disengage the fingers of the ring 25, the spanner pin being of course considerably smaller in diameter than the opening 33 in the hub cap to insure ample play in the manipulating of the spanner to produce the desired result.

45 In the modification shown in Figures XI to XIII inclusive I have provided a relatively short leaf spring 40 which is preferably secured at one end to the inner face of the outer cap member 20 by means of a bolt or rivet 41 as shown in Figure XI. The free end of the leaf spring 40 is provided in one instance with an upstanding pin 42 and in the other with an integral upturned projection 43, each one of which, when in use,

is adapted to extend into locking engagement with the fingers 25' of the ring 25. The leaf springs 40 are each provided at their free ends with downwardly and outwardly inclined portions 44, upon which the 70 pin or projection on the spanner is adapted to ride when the latter is applied to the hub cap, whereby the spring is depressed and the pin 42 or projection 43 moved out of engagement with the finger 25' to permit the cap 75 to be unscrewed from the hub.

While I have shown and described one embodiment of my invention in the present application, it will be understood, of course, that I do not wish to be limited to the particular construction of the parts shown since it will be evident that other forms of construction may be designed without departing from the spirit of the invention when considered in its broadest aspect, as claimed 85 herein.

Having set forth the objects and nature of my invention and the construction embodying the principles thereof, what I claim as new and useful, and desire to secure by 90 Letters Patent is:

1. In a wheel structure comprising a hub and a hub cap having openings therethrough for the reception of a spanner wrench, means for locking said cap to said hub embodying an inherently yieldable member arranged to be attached at one point only to the hub cap and having an outwardly extending projection for engagement with the hub to prevent accidental displacement of the cap upon the hub, and a laterally projecting portion provided with a cam surface adapted to be engaged by the wrench and withdrawn thereby from contact with the hub. 95 100 105

2. In a wheel structure comprising a hub and a hub cap having openings therethrough for the reception of a spanner wrench, means for locking said cap to said hub embodying a spring arranged to be anchored at one end upon the cap and to be free throughout the balance of its length, the opposite end being formed into a loop, and an outwardly extending projection adapted to engage said hub, said loop being inclined away from the plane of the spring to constitute a cam surface by means of which the projection is adapted to be withdrawn by the insertion of the wrench in the said openings. 110 115 120

3. In a wheel structure comprising a hub and a hub cap having openings therethrough for the reception of a spanner wrench, means for locking said cap to said hub embodying a spring member having a bent inclined loop provided with an upstanding projection, said spring member being adapted to be anchored upon said cap with said projection normally extending into locking engagement with said hub, the sides of said 125 130

loop forming a guideway adapted to receive said wrench when the latter is thrust into said openings, the travel of the wrench upon the inclined loop serving to depress the same and thereby to move the said projection to releasing position.

4. In a wheel structure comprising a hub and a hub cap having openings therethrough for the reception of a spanner wrench, 10 means for locking said cap to said hub embodying a locking member formed of spring material, said member being adapted to be anchored at one end upon said cap and having inclined bent portions at the other end, 15 one of said inclined portions being provided with an angular projection normally adapted to extend into locking engagement with

said hub member, said inclined parallel portions forming a guideway for receiving a prong of said wrench when the latter is inserted through the openings in the cap, whereby said prong travels upon the inclined guideway and actuates the locking member to releasing position.

5. A locking member for preventing accidental displacement of a hub cap upon a hub comprising a spring, one end of which is adapted for engagement with said cap and the other end bent to form an inclined tool receiving loop having a locking projection adapted to releasably engage said hub.

In testimony whereof, I affix my signature.

FRANCIS JERDONE, JR.
